(No Model.)

W. P. HALL.
RAILWAY SIGNAL.

No. 578,236.

Patented Mar. 2, 1897.

UNITED STATES PATENT OFFICE.

WILLIAM P. HALL, OF GREENWICH, CONNECTICUT, ASSIGNOR TO THE HALL SIGNAL COMPANY, OF MAINE.

RAILWAY-SIGNAL.

SPECIFICATION forming part of Letters Patent No. 578,236, dated March 2, 1897.

Application filed November 28, 1892. Renewed July 28, 1896. Serial No. 600,856. (No model.)

To all whom it may concern:

Be it known that I, WILLIAM P. HALL, of Greenwich, in the county of Fairfield, State of Connecticut, have invented certain new and 5 useful Improvements in Railway-Signals, of which the following is a specification, reference being had to the accompanying drawings, forming part hereof.

My invention relates to railroad visual signals; and it has for its object to provide a signal that may be operated with a small expenditure of power and will be distinctly visible by day and night and whose operation may be effected electrically and automatically 15 if desired.

My invention consists in the construction hereinafter set forth.

Figure 1 is a rear view of the signaling apparatus with the case partly broken away, 20 showing the day-signal at "danger" and the night danger-signal in its signaling position. Fig. 2 is an enlarged detached view of the mechanism with the signals in the same position. Fig. 3 is a view similar to Fig. 1, with 25 the several signal-disks at "clear." Fig. 4 is a vertical transverse sectional elevation of the apparatus and inclosing case. Figs. 5 and 6 are detail views of the armature and one of the helices of the electromagnet, and 30 Fig. 7 a detail showing construction of pole of magnet.

A represents a plate, which may be the front of a casing A', as shown in the drawings, and carried by a suitable support. This 35 plate is provided with two apertures a a'. When the plate A is part of the casing, the casing has an aperture a³, registering with aperture a, and preferably an aperture a², registering with the aperture a'. Behind the 40 plate A or within the casing are three signal-disks S, R, and G, mounted to turn upon an axis and operated by any suitable motor, so that the disk S may move into and out of register with the aperture a and the disks R and 45 G move alternately into and out of register with the aperture a'. When the disk S registers with aperture a, one of the disks R and G, as R, registers with the aperture a', and when the disk S is out of register with aperture a the other disk, as G, registers with aperture a'. The disk S is intended, as herein

shown, for a day-signal disk, and if it is designed that it shall indicate "danger" it will ordinarily be suitably colored, as, for example, red, being in this case preferably opaque 55 or semiopaque, so as to reflect sunlight. The disks R and G are intended, as herein shown, for night-signal disks, and for this purpose one or both of them should be translucent, so as to transmit and color a beam of light 60 from a lantern, as Z, arranged behind the apertures a' a². If both of the disks R and G are translucent, they would ordinarily be made of differently-colored glass, so that different colors would appear at the aperture a', 65 one for "danger" and the other for "safety." Instead of having both disks R and G translucent one of them might be opaque, in which case the opaque disk would cut off the light from the lantern Z when registering with the 70 aperture a'.

While the embodiment of the invention shown in the drawings contemplates two night-signal disks and one day-disk, it is of course to be understood that the invention 75 includes the reverse of this arrangement—viz., two day-disks and one night-disk.

In the daytime, when the signal-disk S is away from the aperture a, a disk of white sunlight is visible at this aperture to indicate 80 that the track is clear. When the disk is moved before the aperture to indicate "danger," a colored disk is visible at the aperture surrounded by an annulus of white sunlight. If the plate A is, as shown in the drawings, 85 the front of the casing A', then I provide an aperture a³ in the back of the casing directly behind the aperture a. In this latter instance the apertures a and a³ are preferably covered by a plate of glass, and when the signal-disk S is at "danger" the annulus of 90 white sunlight will still be visible around the disk.

Referring now more specifically to the present embodiment of the invention, the actuating mechanism is preferably constructed as follows: The poles d of the electromagnets D D are prolonged laterally, as shown particularly in Figs. 4 and 5, so as to be embraced by wings e e, curved upon the arc of a circle 100 from the same radius, but in opposite directions, and extending from the ends of a bar

of soft iron forming the body of the armature E. This armature is formed in one with or mounted upon the side of a rotary plate E', which is pivoted centrally (slightly below the electromagnets) between the arms f f' of a bracket F, carrying the magnets D, and which bracket is in turn carried by and adapted to be adjusted lengthwise in a grooved bracket F', fastened to the inner face of the front board of the case A'. The arm f of the bracket F has a pin f² projecting into a curved slot e² in the plate E to limit its rotary movement and the consequent travel of the disks S, R, and G. The wings e e of the armature are each made up of two curved plates or arms placed a sufficient distance apart to enable them to straddle or embrace the prolonged poles d of the magnets, so that while free to move thereupon a full and efficient contact is made by the armature with said poles when the magnets are energized, and one arm of each wing is preferably longer than its companion, so as to always remain in close proximity to the poles d when the electromagnets are demagnetized, so as to be easily attracted when the circuit is made and thus economizing battery-power in operating the signal. (See particularly Figs. 2 and 5.)

e' is a connecting pin or brace between the arms of each wing near their outer ends, set to one side, so as to allow the armature to move past the poles to the full end of its throw.

As seen in Figs. 6 and 7, I introduce a spring-pin e³ into a suitable cavity e⁴, formed in the prolonged pole d of the magnet, to afford a yielding impact for the armature when the latter is attracted by the energizing of the magnet, and thus prevent the wear and tear consequent upon the jarring of the parts as heretofore arranged.

The several signal-disks are rigidly connected to the rotary plate E', the day-signal disk S being closely connected by the piece b, and the two night-signal disks R and G are mounted upon the extremities of rods r and g, extending outward from the rotary plate, the disks S and R being on directly opposite sides of the center and the rod of the disk G standing out at right angles thereto, its opposite being a counterbalance-rod H, having an adjustable counterweight h near its extremity. A strap or bar h', curved to properly avoid the bracket F, connects this counterbalance-rod with the rotary plate E'.

The day-signal disk S is usually of red silk stretched upon a light rim, but the night-signal disks R and G should be of colored glass or other transparent or semitransparent material, through which the rays of a lantern Z, mounted in proximity to or upon the case in line with the opening a², will be projected when said lantern is lighted after dark and when either of said signal-disks is in position at the aperture a'. As the night-signal disk R serves to indicate "danger," it is usually colored red, and, as the other night-signal disk G is to indicate "clear," it is usually colored blue, but

any other suitable color may be used. An electric light may be used in place of the ordinary lantern.

Both of the apertures a, a', a², and a³ are covered, preferably, with plain glass to protect the internal mechanism from injury by rain and dust.

The operation of the above-described compound-signal device will be readily understood from the foregoing by those skilled in the art, but I may further explain that the concurrent movement of the three signal-disks and their arrangement in connection with the one armature are such that the disks S and R are exposed at the apertures in the case simultaneously when "danger" is to be indicated, one or other of them being considered as effective, according to whether it is daylight or dark, and upon the retirement of these within the case the aperture a of the day-signal is left clear, but the aperture a' is covered by the colored disk G, which is effective as positively indicating "clear" at night-time.

While the preferred arrangement of causing the signal-disks to go to "danger" by gravity upon the demagnetization of the electromagnets and to go to "clear" upon the magnets being energized is herein described and illustrated in the drawings, it will be apparent that my improved compound day and night signal may be operated in the reverse way and that the details of construction and arrangement of mechanism may be varied without departing from the principle or sacrificing the advantages of my invention.

As above stated, the day-signal aperture a is of greater diameter than the signal disclosed at said aperture, so as to leave an open space b between the rim of the disk and the edge of the aperture or face proper of the case A', this arrangement having been found highly serviceable in enabling engineers of approaching trains to more clearly discern the signal displayed.

What I claim as new, and desire to secure by Letters Patent, is,—

1. In a railway-signal, the combination of a casing having two registering apertures, one in the front and one in the back of the casing for a day-signal and having a third aperture in the front for a night-signal, a day-signal disk within said casing movable before and away from its apertures and mounted upon a shaft, with two or more night-signal disks mounted upon the same shaft and adapted to be made visible at night through said third aperture, substantially as set forth.

2. In a railway-signal, the combination with an inclosing casing having two apertures in the face thereof, one for a day and one for a night signal, a danger day-signal disk of colored material and a night-signal disk of translucent material mounted upon a common shaft and arranged to concurrently indicate "danger" when appearing at said apertures, a supplementary night-signal disk made of

- translucent material mounted upon the said shaft and adapted to indicate "clear" at the night-signal aperture concurrently with the clearing of said danger-signal, armatures 5 mounted upon the said shaft and an electro-magnet adapted to revolve such armatures and thus shift the signals, with means for illuminating said night-signals, substantially as set forth. 50
- 10 3. In a railway-signal, the combination of a casing provided with two registering apertures in front and back for a day-signal and an aperture in front for a night-signal, a day-signal disk and two or more night-signal disks arranged to move in and out of register with their apertures, the day-disk being less in diameter than its apertures whereby when it registers with its apertures an annulus of sunlight surrounds it, substantially as set forth. 55
- 15 4. In a railway-signal, the combination of a plate provided with two apertures, one for a day-signal and one for a night-signal, a day-signal disk and two night-signal disks pivotally mounted behind the plate, the day-signal disk being arranged to move in and out of register with its aperture and the night-signal disks being arranged to move in and out of register with their aperture alternately, substantially as set forth. 60
- 20 5. In a railway-signal, the combination of a casing provided with two registering apertures in front and back for a day-signal, and an aperture in front for a night-signal, a day-signal disk arranged to move in and out of register with its apertures and two night-signal disks arranged to move alternately in and out of register with their aperture, substantially as set forth. 65
- 25 6. In a railway-signal, the combination of a plate provided with two apertures, one for a day-signal and one for a night-signal, a danger day-signal disk and two night-signal disks, one a danger-disk and the other a safety-disk, pivotally mounted behind the plate, the day-signal disk being arranged to move 70
- 30 7. In a railway-signal, the combination of a casing provided with two registering apertures in front and back for a day-signal, and an aperture in front for a night-signal, a danger day-signal disk arranged to move in and out of register with its apertures, and two night-signal disks, one a danger-disk and the other a safety-disk, arranged to move alternately in and out of register with their aperture, substantially as set forth. 75
- 35 8. In a railway-signal, the combination of a casing provided with two registering apertures in front and back for a day-signal, and two registering apertures in front and back for a night-signal, a day-signal disk arranged to move in and out of register with its apertures and two night-signal disks arranged to move alternately in and out of register with their apertures, and a lantern mounted upon the back of the casing behind the night-signal apertures, substantially as set forth. 80
- 40 9. The combination with the case and an electromagnet having prolonged poles, of a rotary plate E', armature E having wings e e, signal-disks S, R and G, all rigidly connected so as to move with said rotary plate and armature, and suitable supporting-brackets, substantially as set forth. 85
- 45 10. In a railway-signal, the combination of a plate provided with two apertures, one for a day-signal and one for a night-signal, three signal-disks pivotally mounted behind said plate so as to move in and out of register with the apertures, whereby two disks register conjointly at both apertures at one time and the third disk registers with one of the apertures at another time, substantially as set forth. 90
